UNITED STATES PATENT OFFICE.

JOSEPH T. CURTIS, OF MILFORD, VIRGINIA, ASSIGNOR OF ONE-HALF TO HENRY K. JOHNSON, JR., OF MILFORD, VIRGINIA, AND ONE-HALF TO BOSSA S. MINGE, OF RICHMOND, VIRGINIA.

GASEOUS-FUEL MIXER.

1,233,558.

Specification of Letters Patent. Patented July 17, 1917.

Application filed June 28, 1916. Serial No. 106,509.

To all whom it may concern:

Be it known that I, JOSEPH T. CURTIS, a citizen of the United States, residing at Milford, in the county of Caroline and State of Virginia, have invented certain new and useful Improvements in Gaseous-Fuel Mixers, of which the following is a full, clear, and exact specification.

This invention relates to devices for promoting the intimate mixture of gas and air for use as fuel for internal combustion engines, and has for its object to provide an improved device of simple construction which may be placed in the pipe leading from the carburetor to the manifold of the engine and which will produce a plurality of oppositely whirling currents in the gaseous mixture drawn through the mixer by the suction of the piston. A further object is to provide for a maximum number of these oppositely whirling currents in order to insure the thorough mixture of the gas and air before reaching the manifold.

The invention will be first hereinafter described in connection with the accompanying drawings and then more specifically defined in the claims at the end of the specification.

In the accompanying drawings, wherein similar reference characters are used to designate corresponding parts throughout the several views:

Figure 1 is an elevation of a carburetor and manifold, the pipe connecting them being partly shown in section and the mixer in elevation.

Fig. 2 is an enlarged broken elevation of the mixer.

Fig. 3 is a plan view of the smaller end portion of the mixer, and

Fig. 4 is a sectional view on the line IV—IV of Fig. 2, drawn to a larger scale.

The carburetor 1 and manifold 2 shown in the drawing may be of any known construction, and the mixer 4 is placed in the pipe 3 leading from the carburetor to the manifold, being secured by having its flange 5 clamped between the meeting ends of the pipe sections. The mixer is formed generally in the shape of a hollow cone in order to leave a surrounding space between its body and the inner wall of the pipe extending to the flange 5.

The mixer is preferably made of sheet metal and in its body are cut a plurality of alternately oppositely inclined encircling

rows of slots 6 and 7. As shown, there are three rows of slots 6 inclined toward the right, one of said rows being adjacent the larger end of the mixer, another adjacent the smaller end thereof, and a third row encircling the middle of the mixer, while there are two rows of slots 7 arranged respectively between the middle row of slots 6 and the rows of slots 6 near the opposite ends of the mixer. Each of the slots 6 and 7 is formed by cutting a slit in the body of the mixer and turning out one edge to form a lip 8, Fig. 4, which together with the incline of the slot serves to impart a whirling motion to the currents of gas and air passing through the slot. It will thus be seen that the three rows of slots 6 will produce currents whirling about the body of the mixer in one direction, while the two rows of slots 7 will produce currents whirling about the body of the mixer in the opposite direction and between the currents formed by the rows of slots 6. In this way, the gas and air in these oppositely moving currents will be most intimately and thoroughly mixed before entering the manifold.

As an additional means of accomplishing the desired object, the smaller end of the body of the mixer is provided with a circular series of curved or inclined blades or fins 9 each overhanging an opening 10 in said smaller end of the mixer. These blades or fins are inclined in the opposite direction to the row of slots 6 near the smaller end of the mixer and serve to create a third whirling current in the same direction as the currents formed by the two rows of slots 7. Thus, three whirling currents will be produced in each direction and the currents in one direction will alternate with those in the opposite direction. Of course, the number of rows of slots in the body of the mixer, the spacing of the slots in each row and the size of the slots may be varied as found necessary or desirable. Being aware that these and other changes in details may be made in the construction herein shown and described without departing from the spirit of my invention, I reserve the right to make such modifications as fairly fall within the scope of the appended claims.

Having thus described my invention, what I claim as new and desire to secure by Letters Patent of the United States is:

1. A gaseous fuel mixer of the character

described consisting of a hollow cone having a plurality of encircling rows of slots therein, the slots in alternate rows being inclined in opposite directions for the purpose specified.

2. A gaseous fuel mixer of the character described consisting of a hollow cone having a plurality of encircling rows of slots therein, and an outwardly turned lip at one edge of each of the slots, the lips being arranged on opposite sides of the slots in alternate rows for directing the gaseous currents passing through said slots in opposite directions around the cone.
- 15 3. A gaseous fuel mixer of the character described consisting of a hollow cone having a plurality of encircling rows of slots therein, and an outwardly turned lip at one edge of each of the slots, the lips being arranged on opposite sides of the slots in alternate rows and the slots in alternate rows being inclined in opposite directions for the purposes specified.
- 20 4. A gaseous fuel mixer of the character described consisting of a hollow cone hav-

ing a central opening in its smaller end, and a circular series of inclined blades overhanging said opening for imparting a whirling movement to the gaseous currents which pass through the same, the cone also having an encircling row of slots formed to direct the gaseous currents which pass through them in the opposite direction to the currents which pass through the opening in the smaller end of the cone.

5. A gaseous fuel mixer of the character described consisting of a hollow cone having a plurality of encircling rows of slots therein, the slots in alternate rows being formed to direct the gaseous currents passing through them in opposite directions, the cone also having a central opening in its smaller end, and inclined blades overhanging said opening for directing the gaseous currents passing therethrough in the opposite direction to the currents passing through the adjacent row of slots.

In testimony whereof I have signed my name to this specification.

JOSEPH T. CURTIS.
